(57) **CLAIM**

The ornamental design for a combined detachable baseball base and support unit, as shown and described.

DESCRIPTION

FIG. 1 is a perspective exploded view of a combined detachable baseball base and support unit of the present invention;

FIG. 2 is a perspective view of the assembled design;
FIG. 3 is an elevational view of the rear and side of FIG. 1;
FIG. 4 is an elevational view of the front of FIG. 1;
FIG. 5 is a top view thereof; and,
FIG. 6 is a bottom view thereof.

The features shown in broken lines are for illustrative purposes only and form no part of the claimed design.
